JULIUS JONAS, OF BADEN, SWITZERLAND, ASSIGNOR TO AKTIENGESELLSCHAFT BROWN, BOVERI & CIE., OF BADEN, SWITZERLAND.

MAGNETICALLY-CONTROLLED MERCURY-VAPOR APPARATUS AND THE LIKE.

1,212,774.

Specification of Letters Patent. Patented Jan. 16, 1917.

Application filed September 12, 1914. Serial No. 861,467.

To all whom it may concern:

Be it known that I, JULIUS JONAS, a subject of the German Emperor, of Bruggerstrasse 22, Baden, Switzerland, have invented certain new and useful Improvements in and Relating to Magnetically-Controlled Mercury-Vapor Apparatus and the like, of which the following is a specification.

This invention relates to apparatus for controlling magnetically influenced mercury vapor electric arcs in a vacuum vessel.

The effect of the controlling magnet is based on the attraction or repulsion of the molecules of vapor that are traversed by current. If the deflection of the stream lines due to the magnet is hindered by any obstacle, for instance a sharp edge or a wall, then there first takes place a magnetic compression of the stream lines toward the obstacle to the deflection, and the consequent contraction of the cross section for the passage of the current produces an increased resistance in the circuit of the electric arc. If the magnet is gradually strengthened, the resistance will rise gradually to a value at which the electric arc will break and the resistance value will finally become infinite.

The broken electric arc does not re-form so long as the magnetic field retains the value necessary for interrupting the current; this can be explained as follows:—It is assumed that in addition to the electrodes proper there are provided also igniting electrodes as is well known see for instance U. S. Patent No. 877,026, through which the current flows permanently and which are not under the influence of the magnetic field. These igniting electrodes energize the main electrodes in such a manner that an electric arc is at once formed between them, as soon as the magnetic field falls below the aforesaid limit value.

The electric arc is produced by the fact that at first ions are thrown off by the cathode and thus reach the anode and constitute a bridge over which the electric arc is formed. The ions are, however, likewise deflected in their course by the magnetic field and are unable to constitute a bridge between the main electrodes so long as the magnetic field has not dropped below the limit value. Consequently by maintaining a corresponding magnet field, the electric

arc current can be permanently interrupted, but only when there is an obstacle to the shifting of the stream lines. Otherwise only a deflection of the electric arc takes place without any substantial increase of resistance.

In the accompanying diagrammatic drawings: Figure 1 is an elevation, and Fig. 2 a part sectional plan of a magnetically controlled mercury vapor cell; Figs. 3 to 9 are part sectional plans of various modifications according to the present invention in which: Fig. 3 shows a form with a comparatively sharp edge for breaking the arc; Fig. 4 shows an arrangement with a tube of rectangular section for containing the arc placed between the poles of a magnet but eccentric thereto, that is to say the center line of the poles is not coincident with the center line of the tube. Fig. 5 illustrates a modification with a tube of triangular section; Fig. 6 indicates a further modification in which the magnet is excited both by direct and by alternating current; Fig. 7 illustrates a magnet with gaps for two vapor cells, and Fig. 8 shows a modification arranged for three-phase current; Fig. 9 illustrates a form in which a single-phase arc is sub-divided into three parts controlled by magnets excited both by direct and by alternating current.

In the well known arrangement shown in Figs. 1 and 2, the wall *q* of the vessel composed of glass constitutes the obstacle to the shifting of the electric arc *l*, and the electric arc is as it were "crushed" against this wall by the field of the magnet *m*. On energizing the magnet with alternating current, there occurs during every half period a field maximum, and if the excitation is sufficiently powerful the electric arc which is generated for instance with direct current, can be extinguished twice during one period of the alternating current. The electric arc direct current is thus converted into a pulsating direct current which can be decomposed into a direct current and an alternating current of double the frequency of the exciting current. This alternating current of double frequency may be utilized for producing high frequency by using it for instance again as an energizing alternating current and thus obtaining alternating current of quad-

ruple frequency, &c. In many cases the doubling of the frequency is not desired and it is then undoubtedly a drawback of the well known arrangement.

5 The object of the present invention is to provide a magnetically controlled mercury vapor lamp free of the disadvantage due to the production of double frequency currents.

10 The invention in brief consists in so arranging matters that the electric arc of the vapor lamp is interrupted only once during each period of the exciting current.

15 In Fig. 3, the controlling magnet m energized by means of alternating current is provided with pole pieces p^1 p^2 whose mutually facing surfaces have the shape of two horns. The density of the lines of force between these faces therefore in different planes is different and is greatest at the 20 point where the pole surfaces are nearest together. At this point there is situated the sharp edge s which is made of conducting or non-conducting and preferably non-magnetic material, serving as an obstacle to the 25 shifting of the electric arc l which when the magnets are not energized, is able to pass through the plane of the figure, say at the point indicated by a dotted circle.

If the magnet be energized by means of 30 alternating current, then the cross section of the electric arc l will move either toward s or away from s . In the latter case no appreciable increase in resistance due to the influence of the magnet will take place, especially as the electric arc moves out of the 35 scope of the field. In the case where l moves toward s , it will come into a field of increasing density and will be pressed against the sharp edge s and finally broken. This 40 breaking thus occurs only during one direction of the exciting current, that is to say, only during one half period in the case of alternating current, while the electric arc remains existent during the other half period.

45 In Fig. 4 instead of the sharp edge s of Fig. 3 a wall or a guide tube r for the electric arc is employed, which tube is located eccentrically for instance in the case of parallel pole surfaces as shown opposite the middle line z of the poles. In the case of energization in the one direction the electric arc is pressed toward the side x and in the other direction the tube is so situated 50 that the arc is shifted toward y . When the arc is magnetically impelled toward side x it will still be in a strong field as it impinges on y and further movement toward this side will result in breaking the arc. 55 Such a result cannot take place in a movement toward y because that side is so far removed from the path of maximum density of field that the repulsion effect becomes negligible before the arc touches the side y .

60 65 In Fig. 5 the tube r has a triangular cross

section for the purpose of moving the electric arc into a field of increasing density when moving toward x .

The object in view may be attained in another way by mixed excitation of the controlling magnet. In the arrangement shown 70 in Fig. 6, a direct current field is superposed on the alternating current field. If the value of the direct current field be equal to the maximum value of the alternating field, then the exciting ampere turns will be added together during the one half period, and will be subtracted during the other half period. If the direct current field be 75 made such that it is just sufficient for interrupting the electric arc led between walls or sharp edges, then the electric arc will be broken during one half period and will be re-formed during the other half period.

In the arrangement shown in Fig. 6, a 80 choking coil d is provided for rendering inoperative the mutual induction of the alternating current winding w upon the direct current winding g of the controlling magnet.

85 When a number of electric arcs are controlled by magnets whose alternating currents are taken from the different phases of a polyphase net, or whose phase difference is the same in passing through the cycle, 90 then the E. M. F.'s, induced in the direct current windings will cancel one another, if the direct current windings of all the magnets are connected in series. It is not 95 then necessary to insert an inductive resistance.

100 Fig. 7 illustrates the case where two electric arcs l^1 l^2 are controlled with a phase shifted 180°. The two magnets are combined to form a double magnet m which 105 although having the two series connected direct current windings g^1 and g^2 , is yet energized by a common alternating current winding w . The alternating field of either half of the magnet is then shifted 180° relatively to the other half of the magnet, and is added to the direct current field in the one half of the magnet, while it is subtracted in the other half. The direct current field passes through j_1 j_2 k_3 p_3 p_2'' p_2' p_1 k_1 , 110 the alternating field passes through k_2 , and is then divided into two parts of which the one part passes through p_2' p_1 k_1 j_1 , and the other passes through p_2' p_3 k_3 j_2 . The E. M. F.'s induced in the two windings g^1 115 and g^2 cancel each other completely.

120 In the form shown in Fig. 8 which applies to a three-phase system the three arcs l_1 l_2 l_3 are inclosed in tubes r_1 r_2 r_3 controlled by the magnet, m , with the three 125 cores k_1 k_2 k_3 carrying alternating current windings w_1 w_2 and w_3 on which are mounted the direct current windings g_1 g_2 g_3 g_4 g_5 and g_6 . The direct current windings are energized from the battery b and the alter- 130

nating current windings from the generator z . The arcs and the magnets are enclosed in the common vacuum vessel g . The direct current flux generated by the coils g_1 — g_6 continues directly by way of the pole pieces p and the arcs l , in the order of succession $p_1 l_3 p_2' p_2 l_1 p_3' p_3 l_2 p_1' p_1$, while the flux of the three coils $w_1 w_2 w_3$ changes according to the momentary value of the three phase currents. For instance, if the coil w_1 has a momentary maximum positive terminal potential and if at the same time the other two coils w_2 and w_3 have half the negative terminal potential, then at that moment the maximum flux generated by them is divided from the core k_1 on the one hand through $p_1 l_3 p_2' k_2$ and the yoke m , and on the other hand through $p_1' l_2 p_3 k_3$ and m back to k_1 . Next k_2 has the strongest field, then k_3 and so on. There is in fact a three-phase field. As will be seen, at that moment in the path $p_1 l_3 p_2'$ the alternating field is added to the direct current field, whereas in the path $p_1' l_2 p_3$ it is subtracted from the direct current field, while in the path $p_2 l_1 p_3'$ it is *nil*. The path of the direct current field is marked I, and the path of the momentary value (given by way of example) of the alternating field (three-phase field) is marked II.

The direction of the direct current ampere turns must be so chosen that the shifting of the electric arc in the case of the adding together of the direct current field and alternating current field shall take place into the field of increasing density (in Fig. 8 therefore toward the axis of the cylindrical vessel). It is an advantage to cause the electric arc to shift toward the interior of the vessel because this allows of a convenient way of cooling and carrying off the heat (e. g. by parts c referred to below) for it is required to carry off in a suitable manner the losses of energy which occur in the electric arc by reason of the increase of resistance therein.

The windings must be so arranged that the heat generated in the electric arc shall not pass over to them. For this purpose the windings are arranged as far as possible at the periphery of the vessel where they can be effectively cooled from the outside.

In Fig. 9 each electric arc is divided into a number of partial arcs, and an equal number of simultaneously energized magnets made to act upon these partial arcs, the magnets being arranged in such a manner that each partial arc is situated between the north pole of one magnet and the south pole of the other magnet. The form illustrated in Fig. 9 comprises a mono-phase electric arc which is divided into three partial arcs. These partial arcs are connected up in parallel and are intended to be all extinguished simultaneously by the controlling magnets,

and to be all lighted up again simultaneously by the igniting apparatus.

Fig. 9 is merely a triplication of Fig. 6, in which the three parts are contained in a common vessel. The flux has its course 70 along the line III, that is to say the direct current field has always the direction of the arrows I, while the alternating current field has alternately the same or the opposite direction, as indicated by the arrows II 75 and IV.

As with Fig. 8 a battery b is provided for exciting the direct current windings and a generator z for the alternating current field. In addition an inductance d is illustrated as in Fig. 6. It has been assumed that the coils are connected in series, but they might have been connected in parallel. In this arrangement the windings do not come in contact at all with the guiding tubes 80 of the electric arcs. If the electric arcs be shifted toward the interior of the vessel for the purpose of being broken, then the resulting losses will also occur in the interior of the vessel, where they are carried off to the 85 outside by a system of cooling pipes which is provided with cooling ribs c c' and is traversed by cooling fluid. This system of cooling pipes is preferably made of non-magnetic material. 95

The cooling fluid may be admitted through the inner pipe c' of the cooling pipe system and be discharged through the outer pipe c so that the entire system requires only one aperture for admittance into 100 the vacuum vessel.

In Fig. 9 both as regards the direct current excitation, as well as regards the alternating current excitation there is always a south pole arranged opposite a north pole so 105 that every utilizable line of force traverses all three electric arcs.

It is an advantage to make the windings of enameled wire, because such wire is free from the porosity which would hinder the 110 formation and maintenance of a good vacuum, and also because enameled wire is resistant to heat and can be cooled more easily than wire which is insulated in the ordinary way. Enamel has the further property 115 (which is especially valuable in the case of mercury vapor cells) of preventing the amalgamation of the wire and of itself being unattacked by mercury.

The particular form of pole pieces and 120 obstacles shown in Figs. 3 to 5 may also be employed in the case of a magnet with mixed energization.

Instead of the constant direct current a pulsating direct current may be employed. 125

In the arrangement shown in Fig. 7 the common winding w may be excited by direct current, and the other windings g^1 and g^2 by alternating current.

The arrangement shown in Fig. 7 may 130

also for example as shown in Fig. 8 be applied to three electric arcs controlled with a phase difference of 120° , as well as generally to polyphase arrangements of any 5 desired number of phases.

Having now described my invention, what I claim as new and desire to secure by Letters Patent is:—

1. In combination a mercury vapor apparatus or the like, a controlling electromagnet disposed in proximity thereto, means for supplying current of varying direction to said magnet and means for interrupting the electric arc of the vapor apparatus, only once during one period of the exciting current.

2. In combination a mercury vapor lamp or the like including a guiding tube for the arc, an electromagnet with tapering pole faces disposed in proximity to said tube but eccentric thereto and means for supplying an alternating current to the winding of said electromagnet in such a manner that once for every period of this current the arc 25 is driven into a field of such density that it is broken.

3. In combination a mercury vapor lamp or the like, including a guiding tube for the

arc, an electromagnet with two windings and with tapering pole faces, said magnet 30 being disposed in proximity to said tube but eccentric thereto, means for supplying an alternating current to one winding of the electromagnet, and means for supplying a direct current to the other winding of the 35 electromagnet, the currents being such that once for every period of this current the arc is driven into a field of such density that it is broken.

4. In combination a mercury vapor lamp 40 or the like including a guiding tube for the arc, an electromagnet disposed in proximity to said tube but eccentric thereto, two windings on said magnet, means for supplying an alternating current to one winding and 45 means for supplying a direct current to the other winding, the currents being such that once for every period of this current the arc is driven into a field of such density that it is broken.

In testimony whereof, I have affixed my signature in presence of two witnesses.

JULIUS JONAS.
